UNITED STATES PATENT OFFICE.

HENRY J. SANDLASS, OF FOREST PARK, MARYLAND.

DESIGN FOR A KEY-BED FOR PIANOS.

55,888.

Specification for Design.

Patented July 20, 1920.

Application filed March 24, 1917. Serial No. 157,276. Term of patent 14 years.

To all whom it may concern:

Be it known that I, HENRY J. SANDLASS, a citizen of the United States of America, residing in Forest Park, in the county of Baltimore and State of Maryland, (whose post-office address is 4309 Liberty Heights avenue, Forest Park, Baltimore county, Maryland,) have invented a new and ornamental Design for a Key-Bed for Pianos, of which the following description, in connection with the accompanying drawing, is a specification.

The single figure of the drawing is a perspective view of a key bed for pianos showing my new design. The dotted lines of the figure indicate that the key bed design may be used in conjunction with a grand piano or an upright piano.

I claim as my invention:

The ornamental design for a key bed for pianos, as shown.

HENRY J. SANDLASS.
